UNITED STATES PATENT OFFICE.

WILLIAM B. HOWARD, OF BROOKLYN, NEW YORK, ASSIGNOR TO HOWARD & MORSE, OF NEW YORK, N. Y., A FIRM.

SHAKING-BOLT.

No. 857,942.

Specification of Letters Patent.

Patented June 25, 1907.

Application filed October 12, 1906. Serial No. 338,563.

To all whom it may concern:

Be it known that I, WILLIAM B. HOWARD, a citizen of the United States, residing at the borough of Brooklyn, in the county of 5 Kings and State of New York, have invented certain new and useful Improvements in Shaking-Bolts, of which the following is a specification, reference being had therein to the accompanying drawing.

10 This invention relates to sieves for separating, gaging and testing substances such as sand, cement, ores, drugs, or any other substance which the invention is capable of manipulating.

15 The invention consists in a machine adapted for such uses, comprising in the present embodiment a series of sieves of varying mesh superposed and mounted upon a supporting base to which is imparted a motion

20 similar to the gyratory and vertical shaking movement practiced in operating a sieve by hand shaking, this movement being herein referred to, mechanically, as a horizontal gyrating reversing motion and which spreads

25 the contained substance over the surface of the sieve and an intermittent vertical motion coincident with each reverse movement that produces a succession of shocks or jars and causes the finer particles to separate and

30 pass through the mesh.

In the use of a series of sieves superposed as shown in the present instance, the mesh is of different size beginning with a coarser or larger mesh in the uppermost sieve and in the 35 succeeding sieves employing a gradually decreasing size of mesh, which may be suited to the degree of fineness desired.

In the use of the invention any number of sieves may be employed, according to the nature of the substance to be acted upon and the sieves may be transposed or disposed in sets and placed in any relative position found necessary.

40 In the accompanying drawing forming a part of this specification, a machine is illustrated, embodying the invention in which

Figure 1 is an elevation in perspective, Fig. 2 an enlarged front view partly in section, and Fig. 3 a plan or top view showing a 45 relative position of some of the operative parts and the paths of gyration imparted thereto.

The machine shown is designed to be oper-

ated by hand, but any power devices may be substituted.

55 Referring to the drawing, in which the corresponding parts are designated by the same numerals in each figure, 4 represents the base of the machine to which is secured the supports 5 and 6 upon which the driving mechanism is mounted, comprising the spur gear 7 with attached handle 8 and beveled gears 9—10, and through which the horizontal movement of the sieves is transmitted. The vertical shaft 2 of the bevel gear 10 is 60 stepped at its base and rests upon the spring 11 for the purpose of relieving the jar occasioned by the intermittent vertical movement of the sieve carrier 12. This vertical intermittent movement of the sieve carrier 65 70 75 12 is produced by the engagement of the bumper 13 depending from its base with the idle rollers 14 attached to the fixed plate 15 in the sweep of the gyrating base of the carrier. These rollers 14 are located and fixed upon opposite parts of the periphery of the plate 15, and project above the plate to cause the vertical movement of the sieve holder when contacting intermittently with the bumper 13.

The base of the sieve carrier 12 is made in 80 a cup form iron casting having a circular plate or disk 16 set in its bottom and which is allowed to rotate therein through the medium of its grooved periphery, as shown at 17 in Fig. 2. This plate or disk 16 is fixed to 85 the vertical shaft 2 eccentrically, as shown in Fig. 2, and the horizontal gyrating movement of the carrier 12 is derived therefrom. This horizontal gyrating movement of the sieve carrier, derived as explained, is guided 90 and controlled in its reversing motion by means of the depending pin 18 which is fixed to the bottom of the carrier and engages with a radial slot 19 in the fixed plate 15, as shown in the respective figures. This pin 18 95 is moved radially within the slot 19 by the gyrating movement of the carrier, the latter rotating on the pin.

100 20 represents vertical tie rods arranged upon and fixed to opposite sides of the base of the sieve carrier and which are provided with screw hand wheels 21 at the top, these rods serving in connection with a top plate 22 to inclose and hold any number of the series of sieves in place.

105 The movement of the various operative

parts of the machine will be readily understood by an inspection of the drawing, the horizontal movement of the sieve carrier being derived directly through the connected 5 gears and the gyrating reversing motion derived from the rotation of the eccentric disk located in its base, the latter being guided and controlled by the depending pin and slot engagement as heretofore described.

10 The various positions assumed by the sieve carrier during its horizontal movement are indicated in the dotted lines 23—24—25 in Fig. 3.

15 What I desire to claim and secure by Letters-Patent is:—

In a self-contained shaking bolt the combination with a series of superposed and in-

terchangeable sieves, of a carrier having a horizontal gyrating reversing movement on the vertical shaft 2 by means of the engaging 20 circular disk 16 fixed eccentrically to said shaft; a vertical intermittent movement at each gyration by means of the bumpers 13 and engaging rollers 14; a supporting base beneath said carrier inclosing the transmitting operating devices for effecting the said movements, and a connected power device for operating the same.

In testimony whereof I affix my signature in presence of two witnesses.

WILLIAM B. HOWARD.
